J. D. Bryant,
Attorney

UNITED STATES PATENT OFFICE.

STEPHEN KAMENEC, OF DERRY, PENNSYLVANIA.

MATCH BOX.

Application filed March 29, 1923. Serial No. 628,523.

To all whom it may concern:

Be it known that I, STEPHEN KAMENEC, a citizen of Czechoslovakia, residing at Derry, in the county of Westmoreland and State of Pennsylvania, have invented certain new and useful Improvements in Match Boxes, of which the following is a specification.

This invention relates to certain new and useful improvements in match boxes and has for its primary object to provide a match box of the dispensing type wherein a casing or receptacle providing a housing for a plurality of matches has a slide delivery member associated therewith for dispensing several matches at a single operation.

Another object of the invention is to provide an improved type of cover for a receptacle of the above type and a locking means for retaining the receptacle suspended upon a nail or hook.

With the above and other objects in view as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

Figure 1 is a front elevational view, partly broken away and shown in section of a match receptacle constructed in accordance with the present invention showing the tensioned slide drawer for delivery matches from the receptacle and the latch plate for retaining the receptacle suspended upon a hook,

Figure 2 is a edge elevational view of the device,

Figure 3 is a horizontal sectional view taken on line III—III of Fig. 1,

Figure 4 is a detail sectional view taken on line IV—IV of Fig. 1 showing the latch arm for retaining the cover in closed position on the receptacle,

Figure 5 is a detail sectional view taken on line V—V of Fig. 1 showing the slide drawer within the lower end of the dispensing receptacle,

Figure 6 is a perspective view of the retaining latch plate for engaging the suspending hook, and

Figure 7 is a perspective view of the sliding drawer for delivering the matches.

Referring more in detail to the accompanying drawing, there is illustrated a match dispensing receptacle embodying a casing having a front and rear wall 1 and 2 respectively, and end walls 3, the front and rear walls 1 and 2 tapering at their lower ends as at 1^a and 2^a respectively and merging into a substantially U-shaped pocket 4 at the lower ends thereof as shown in Fig. 5.

To accommodate the suspension of the receptacle, as by hanging upon a hook or the like, the rear wall 2 carries an upwardly extending plate extension 5 having a hook receiving opening 6 as shown in Fig. 1. A latch plate is associated with the hook receiving opening 6 for engagement with a hook to retain the receptacle against accidental disengagement therefrom, a spring arm 7, as shown in Fig. 1 being anchored as at 8 to the plate 5 with the upper arched end thereof confined within the clamp 9 projecting laterally from the latch plate 10 that is pivotally mounted as at 11 upon the plate 5; the upper edge of the latch 10 being notched as at 12 that registers with the hook receiving opening 6 for engagement with the hook at a point inwardly of the headed end thereof.

The upper edges of the end wall 3 are bent to provide inwardly directed guide flanges 13 for a sliding cover 14, the outer edge of the sliding cover having a downwardly rolled edge 15 limiting sliding movement of the cover towards its closing position, while the intermediate portion of the forward edge of the cover is bent upwardly as at 16 to provide a hand grip therefor. To retain the cover in a closed position upon the receptacle, a latch arm 17 pivotally mounted as at 18 upon the cover 14 and having an upwardly extending bent portion 19 forming a finger grip, carries at the forward end a depending lug 20 that is projected through an opening 21 in the cover 14 and is adapted to abut the upper edge of the front wall 1 when in its closed position as shown in Fig. 4, upward movement of the latch 17 to the dotted line position illustrated in Fig. 4, permitting outward sliding movement of the cover to permit access to the interior of the receptacle.

A tensioned sliding drawer is associated with the lower U-shaped end 4 of the receptacle for dispensing matches therefrom as indicated by dotted lines in Fig. 1, the

drawer being substantially U-shaped in cross section as indicated in Fig. 5 and including side walls 22 that are cutaway as at 23 adjacent one end thereof with the upper edges of the cutaway portions 23 notched as at 24, the outer end of the drawer carrying an end wall 25 substantially equal in height to the side walls 22, while the inner end of the drawer is closed by an end wall 26. A rod 27 projects outwardly from the end wall 26 and slidably extends through an opening provided in the lower end of the receptacle, a coil spring 28 surrounding the rod 27 and engaging at its inner end, the outer face of the adjacent end wall 3, while the other end of the spring engages the head 29 at the outer end of the rod. The other end wall 3 at the lower end, as shown in Fig. 1, is cutaway as at 30 to permit the sliding drawer to be projected therethrough as shown by dotted lines, an inwardly positioned baffle wall 31 carried by the end wall 3 adjacent the cutaway portion 30 limiting the number of matches to be delivered from the receptacle by the drawer.

From the above detail description of the device, it is believed that the construction and operation thereof will at once be apparent, it being noted that the receptacle is properly retained upon a suspending hook by the latch plate 10 against accidental disengagement while the latch plate 17 associated with the cover 14 and front wall 1 properly retains the cover in position. Pressure upon the head 29 of the rod 27 against the tension of the spring 28, moves the sliding drawer 22 outwardly of the receptacle with several matches contained therein as indicated in Fig. 5, the baffle plate 31 limiting the number of matches being delivered while the cutaway walls 23 and notches 24 permit ready removal of the matches from the drawer. When pressure is relieved upon the rods 27, the spring 28 returns the sliding drawer to its housed position within the receptacle and permit the

deposit therein of additional matches for later delivery.

While there is herein shown and described the preferred embodiment of the present invention, it is nevertheless to be understood that minor changes may be made therein without departing from the spirit and scope of the invention as claimed.

What is claimed as new is:—

1. In a match dispensing apparatus, a receptacle, the lower end of the receptacle tapering to form a transverse U-shaped pocket open at one end, a drawer longitudinally slidably mounted in the pocket and open at its upper side for the deposit of matches from the receptacle and adapted to be projected through the open end of the pocket, the drawer being substantially U-shaped in cross section with the sides thereof adjacent the projected end cutaway to facilitate removal of matches therefrom, means carried by one end of said drawer and projecting through an aperture in the closed end of said pocket for manually operating said drawer, and means associated with said last mentioned means and said closed pocket end for returning said drawer to its inoperative position.

2. In a match dispensing apparatus, a receptacle, the lower end of the receptacle tapering to form a transverse pocket open at one end, a drawer slidably mounted in the pocket and open at its upper side for the deposit of matches from the receptacle and adapted to be projected through the open end of the pocket, the drawer being substantially U-shaped in cross section with the sides thereof adjacent the projected end cutaway to facilitate removal of matches therefrom, a rod extending from the other end of the drawer and slidably projecting through the receptacle and a spring associated with the rod and receptacle to place the drawer under tension.

In testimony whereof I affix my signature.

STEPHEN KAMENEC.
